DESIGN FOR A DISPLAY DEVICE FOR PAINTS OR THE LIKE

Ernst Borregard, Long Island City, N. Y.

Application August 1, 1941, Serial No. 102,621

Term of patent 7 years

To all whom it may concern:

Be it known that I, Ernst Borregard, a citizen of the United States of America and resident of Long Island City, county of Queens, and State of New York, have invented a new, original, and ornamental Design for a Display Device for Paints or the like, of which the following is a specification, reference being had to the accompanying drawing, forming part thereof.

In the accompanying drawing:

Fig. 1 is a front elevational view of a display

device for paints or the like showing my new design;

Fig. 2 is a rear elevational view thereof; and

Fig. 3 is a side edge view thereof.

The essential features of the design reside in the portions shown in full lines.

I claim:

The ornamental design for a display device for paints or the like as shown and described.

ERNST BORREGARD.
